UNITED STATES PATENT OFFICE.

JOHN R. SUPPER, OF PHILADELPHIA, PENNSYLVANIA.

RANGE.

No. 914,085.

Specification of Letters Patent.

Patented March 2, 1909.

Application filed May 26, 1905. Serial No. 262,425.

To all whom it may concern:

Be it known that I, JOHN R. SUPPER, a citizen of the United States, residing in the city and county of Philadelphia, State of Pennsylvania, have invented a new and useful Range, of which the following is a specification.

This invention pertains to improvements in ranges and it has for its objects among others to provide a novel construction of range adapted to increase the amount of water heating surface.

It further consists of novel features of construction, all of which will be hereinafter fully set forth.

Figure 1 represents a front elevation of a range embodying my invention. Fig. 2 represents a side elevation of the same. Fig. 3 represents a vertical section of Fig. 2 upon line *w*—*w*. Fig. 4 represents a perspective view of a portion of my range having the top and front plates broken away so as to show a portion of the interior construction. Fig. 5 represents a top plan view of the construction shown in Fig. 4, a portion of the frame being broken away to show the interior construction. Fig. 6 represents a longitudinal section of Fig. 5 upon line *x*—*x*. Fig. 7 represents a cross section of Fig. 5 upon line *y*—*y*. Fig. 8 represents a perspective view of one of the sections shown in Figs. 1 and 2. Fig. 9 represents a cross section of Fig. 8 on line *z*—*z*. Fig. 10 represents a fragmentary view similar to Fig. 7 showing a different position of one of the parts. Fig. 11 is a horizontal section through Fig. 4 taken above the baffle plate. Fig. 12 is an enlarged detail showing the connection between the house pipe of the water back and the boiler system.

Similar numerals of reference indicate corresponding parts in the figures.

Referring to the drawings, 1 designates the frame of my range, which comprises the front plate 2 having a flange 3, the rear plate 4, which as shown is part of a water casing, the end plates 5 and 6 and the top plate 9.

The inner walls of my range are formed of hollow chambers 10, 11, 12 and 13, which are adapted to be filled with water to increase the water heating surface exposed to the heat of the range. These chambers are interconnected by the connection of the

chambers 10, 11 and 12, each to chamber 13 and by the provision of pipes 14 and 15 between chambers 11 and 12.

In the top of the fire pot and below the top plate 9, I form a coil 16 which is connected by pipes 17 and 18 with the hot water boiler 19 in the usual manner. The interior of the fire pot is provided with projections or depressions of preferably thimble form as 20 to increase the radiating surface. The cross connecting chamber 21 also forms a connection between the chambers 10 and 11 at the same time that it constitutes the front of the fire pot. Upon the back of the range and connected to chamber 13, I place boxes 22 and 23, alternately of different constructions, connecting the first to the chamber 13 and the others to each other by means of ferrules 24 in such manner that there is a complete vertical passage 25 formed, preferably at each end as shown, for the passage of water in the direction as shown by the arrows from the chamber 13 to the pipes 26 and 27 at the top of the back of the range. The boxes 22 are provided with central apertures 27 and the boxes 23 are provided with side apertures 28, preferably upon each side thereof, for the passage of the gases of combustion. Each box is provided with an aperture 29, which, as best shown in Figs. 8 and 9, does not extend through quite the entire length, width or height of the box, but forms a distributing passage for the hot gases from which passage they are conducted through the central aperture of one box to the side aperture of the box above, or vice versa, also increasing the heating surface for the water within these boxes.

I thus provide a water system comprising the side walls for the heating surface of the range, the back of the range and the vertical back portion in the rear of the range leading up to the position in which the hot water boiler is placed, as shown, and connecting with the vertical pipes 26 and 27, as indicated. The water is returned through return pipes to the pipes 59 and 60 so that a complete circulatory system exists at all times.

The hot gases from the fire pot 31 are conducted across the top of the chamber 11 into the air flue 32, which is formed between the upper surface 33 of the baking oven 34 and the top plate 9 of the range. The gases are

then conducted between these plates 9 and 33 downwardly through the passage 35 formed between chamber 12 and the side wall 34' of the baking oven, beneath this 5 oven through the passage 36 formed beneath said oven, vertically through the passage 37 formed between chamber 11 and the side wall 38 of the baking oven, through the opening 39 into the passage 40 formed by walls 41 and 10 42 and door 43 and the top 9 of the range into the smoke passage 44 thence into the smoke pipe. Door 43 is hinged at 45 and is controlled by rod 46. Within the chambers 10, 11 and 12 and at any other points desired, 15 may be arranged baffle plates 47 which require that the water in its passage through these various chambers shall circulate properly throughout them. I form dust doors 48 in the front of the boxes 22 and 23, as best 20 seen in Figs. 1 and 8. I connect my auxiliary system to the house pipe 49 by means of a lateral pipe 49' in which is a valve 49^x, as seen clearly in Fig. 12. The reason for this connection is that it is necessary at times to 25 increase or reduce the amount of water in the system, which former I do by admitting more water from the city system, which correspondingly forces more water into the main pipe of my radiating system.

30 The return pipes 59 and 60 of the system connect with any suitable portion as the chambers 10 and 12 of my interconnected water system within the range.

It will be evident that the hot water system 35 may have its outgoing and return pipes connected directly to the hot water boiler, although in such case there would be a drain by the house needs and consequent reduction of temperature in the radiators.

40 The operation is as follows:—The water is supplied from the city pressure to the hot water boiler and water back and, as already described, to the house system to keep it up to normal quantity. The cold water is in- 45 troduced at the lower part of the system within the range at any suitable point or points and is withdrawn at the upper part of this system at the top of the upper section or box at the back of the range.

50 The door 43 when in place, as shown in Fig. 4, requires that the gases shall pass across the top of the oven and completely around it and enter the smoke flue through opening 39 and passage 44, whereas, when 55 the door 43 has been turned down to the position parallel with the top of the oven by means of rod 46 the gases from the fire pot can pass directly to the smoke flue without passing around the oven.

60 It will be evident that various changes may be made by those skilled in the art, which may come within the scope of my invention and I do not therefore desire to be

limited in every instance to the exact construction herein shown and described.

Having thus described my invention, what I claim as new and desire to secure by Letters Patent, is:—

1. In a device of the character described, a range having a hot water circulation and back for said range, comprising a plurality of separable communicating water receivers, a hot water boiler lying against said back in indirect communication with said receivers, a hot water coil connected with said boiler, 70 means for causing circulation of hot gases between said receivers, and means for the circulation of water.

2. In a device of the character described, an oven, hollow walls inclosing said oven with interconnecting means forming chambers, a transverse chamber connecting two adjacent chambers and forming the front of the fire pot, hollow boxes at the back of the range and connected with said chambers, 80 and having side and central apertures, and a distributing passage for the hot gases.

3. In a device of the character described, a complete intercommunicating water system formed of hollow side walls for the heating surface of the range, a hollow water back with passages for the products of combustion extended above the top of the range, a hot water boiler adjacent the upper end of said back and in indirect communication with said 90 back, and pipes leading from the upper portion of said back.

4. In a device of the character described, a complete intercommunicating water system formed of hollow side walls for the heating surface of the range, a hollow water back with passages for the products of combustion extended above the top of the range, a hot water boiler adjacent the upper end of said back in indirect communication with said 100 back, and pipes leading from the upper portion of said back, and an oven between said hollow walls and having passages upon its sides.

5. In a device of the character described, a complete intercommunicating water system formed of hollow side walls for the heating surface of the range, a hollow water back with passages for the products of combustion extended above the top of the range, a hot water boiler adjacent the upper end of said back in indirect communication with said back, pipes leading from the upper portion of said back, an oven between said hollow walls and having passages upon its sides, and means for causing the gases to pass 11 across the top of said oven and completely around it.

JOHN R. SUPPER.
